UNITED STATES PATENT OFFICE.

ORBY BERTRAM CROWELL, OF TORONTO, ONTARIO, CANADA, ASSIGNOR TO THE
CANADIAN I. T. S. RUBBER COMPANY, LIMITED, OF TORONTO, ONTARIO, CANADA.

BOOK COVER.

Application filed September 18, 1922. Serial No. 588,868.

To all whom it may concern:

Be it known that I, ORBY BERTRAM CROWELL, a subject of the King of Great Britain, and resident of the city of Toronto, county of York, Province of Ontario, in the Dominion of Canada, have invented certain new and useful Improvements in Book Covers, described in the following specification and illustrated in the accompanying drawings, that form part of the same.

The principal object of this invention is to devise a book cover particularly adapted for ring binder type of loose leaf books which will be practically indestructible and will retain its shape indefinitely.

The principal feature of the invention consists on moulding the cover of a rubber material and reducing the cross sectional area at the hinge portions.

In the drawings Figure 1 is a sectional view of a cover constructed in accordance with this invention, showing a nut embedded to receive the screws for holding the metal binder mechanism.

Figure 2 is a sectional view showing the method of moulding the cover.

Figure 3 is a sectional view showing a modified structure with reinforced hinge portions.

It has been the usual custom to manufacture book covers of the ring binder type of leather or flexible fabrics but these are extremely expensive and wear out very quickly. The present invention contemplates the use of a rubber material of sufficient hardness and thickness to form an effective protection to the leaves of the book and of a desired flexibility.

In the form of the invention illustrated in Figure 1 the covers 1 are formed of a sheet of rubber material integrally connected with the back 2, the material being reduced in thickness at the point of connection between the covers and the back. This reduced portion 3 is sufficiently thin to be of a flexibility to allow the cover to be turned back quite readily, the thin portion form-

ing a very flexible hinge. The back portion 2 is preferably thicker than the covers 1 and where used for the ring binder type 50 of cover has suitable fastening nuts 4 moulded therein.

In making the covers the sheet rubber material is placed upon a mould face 5 and the upper section of the mould is provided with 55 ribs 6 and an intervening transverse hollow portion 7 which, when pressure is applied, forms the rubber material into the back 2 and hinges 3. The nuts 4 are moulded into place in the moulding of the cover.

It may be found desirable in certain forms of covers to reinforce the hinges and in Figure 3 I show the cover with a reinforcement 8 of textile fabric molded into the back 2 and extending through the hinge portions 3 into the covers 1.

The invention is herein shown applied to the ring type of binder but of course it will be understood that it may be applied to other forms of books.

What I claim as my invention is:

1. A book cover formed of a moulded sheet of flexible rubber material having a portion of the cross sectional area of a reduced thickness to produce a portion of a greater flexibility than the main body to form a hinge. 75

2. A book cover formed of flexible rubber material having narrow parallel strips of reduced thickness extending thereacross forming flexible hinges, the portion between said 80 hinges being of greater thickness than the main portions and forming a back, and means moulded in said back for securing the leaf binder.

3. A book cover, comprising, a body of 85 flexible rubber material moulded to shape with thin strips connecting the back portion with the cover, a reinforcing fabric embedded in the back and extending across the thin strips, and means for securing the 90 leaves of the book moulded into the rubber material.

ORBY BERTRAM CROWELL.
